(57) **CLAIM**

The ornamental design for a fishing rod with spiral fishing line guides, as shown and described.

DESCRIPTION

FIG. 1 shows a perspective view of a fishing rod with spiral fishing line guides showing my new design;

FIG. 2 shows a right side view thereof;

FIG. 3 shows a left side view thereof;

FIG. 4 shows a front view thereof;

FIG. 5 shows a rear view thereof;

FIG. 6 shows a top plan view thereof;

FIG. 7 shows a bottom plan view thereof;

FIG. 8 shows a perspective view of another embodiment of a fishing rod with spiral fishing line guides showing my new design;

FIG. 9 shows a right side view thereof;

FIG. 10 shows a left side view thereof;

FIG. 11 shows a front view thereof;

FIG. 12 shows a rear view thereof;

FIG. 13 shows a top plan view thereof; and,

FIG. 14 shows a bottom plan view thereof.

The shade lines in the Figures show contour and not surface ornamentation.

The broken lines shown in the Figures show portions of the fishing rod with spiral fishing line guides which form no part of the claimed design.

1 Claim, 8 Drawing Sheets
